ABSTRACT

A fluid-pressure-operated reciprocating motor having a spool and piston slidable in spool and piston cylinders respectively in which the spool has a first pair of opposed faces which respectively communicate with a pair of spool-working chambers, and a second pair of opposed faces which respectively communicate with a pair of spool-biasing chambers, and the piston is double acting and has a pair of opposed faces which respectively communicate with a pair of piston chambers, reversal of the piston being initiated by reversal of the spool which serves to connect one piston chamber alternately to fluid pressure and to exhaust and to connect the other piston chamber alternately to exhaust and to fluid pressure respectively; in which the timing of reversal of the spool is determined according to the position of the piston in its cylinder, and the motor is so arranged that, with the spool at an end of its stroke, one spool-working chamber is open to pressure while the other spool-working chamber is open to exhaust to urge the spool to that end and one spool-biasing chamber is open to exhaust and, to reverse the spool, fluid pressure in both spool-working chambers is caused to apply equal and opposite axial thrusts on the spool and pressure is caused to be admitted to the other spool-biasing chamber in opposition to the load on the spool applied by fluid pressure in said one spool-working chamber.

FLUID-PRESSURE-OPERATED MOTORS

This invention relates to fluid-pressure-operated motors and is particularly directed to such a motor for producing reciprocatory motion.

It has hitherto been proposed to provide a fluid-pressure-operated motor of the type in which a spool, axially slidable in a spool cylinder, controls reciprocation of a piston which is axially slidible in a piston cylinder and the position of the piston in its cylinder controls axial movement of the spool. In such motors the piston is generally double acting and movement of the spool affected by variations in fluid pressure applied to a pair of opposed faces on the spool.

In accordance with the present invention there is provided a fluid-pressure-operated motor for producing reciprocating motion which includes;

a spool axially slidable in a spool cylinder, the spool having a first pair of opposed faces each of which respectively communicates with one of a pair of spool-working chambers in the spool cylinder, and a second pair of opposed faces each of which respectively communicates with one of a pair of spool-biasing chambers in the spool cylinder;

a piston axially slidable in a piston cylinder, the piston being double acting and having a pair of opposed faces each of which respectively communicates with one of a pair of piston chambers, reversal of the piston being initiated by reversal of the spool which serves to connect one piston chamber alternately to fluid pressure and to exhaust and to connect the other piston chamber alternately to exhaust and to fluid pressure respectively;

and wherein the timing of reversal of the spool is determined according to the position of the piston in its cylinder, the arrangement being such that with the spool at an end of its stroke, one spool-working chamber is open to fluid pressure while the other spool-working chamber is open to exhaust to urge the spool to that end and one spool-biasing chamber is open to exhaust and, to reverse the spool, fluid pressure in both spool-working chambers is caused to apply equal and opposite axial thrusts on the spool and fluid pressure is caused to be admitted to the other spool-biasing chamber in opposition to the load on the spool applied by fluid pressure in said one spool-working chamber.

It is to be realized that by the term "fluid" as used throughout this specification we include both liquids (hydraulically operated motors) and gases (pneumatically operated motors).

To reverse the spool, fluid pressure in both spool-working chambers is so arranged that the axial thrusts on the spool from such fluid pressure or pressures in the spool-working chambers are equal and opposite, and movement of the spool from its end of stroke position is achieved by applying fluid pressure in said other spool-biasing chamber while said one spool-biasing chamber is open to exhaust. Equal and opposite axial thrust on the spool from the spool-working chambers may be achieved by having the first pair of opposed faces of the spool of different effective area and by providing a corresponding difference in fluid pressure which is applied to each of the pair of spool-working chambers. For example, if the effective areas of the first pair of opposed faces of the spool are in the ratio 2:1, then the fluid pressure in the spool-working chambers are so arranged that, at reversal of the spool, fluid pressure in the spool-working chamber which communicates with the face of smaller effective area is in the ratio of 2:1 with fluid pressure in the spool-working chamber which communicates with the face of larger effective area, thereby providing equal and opposite axial thrust on the piston. However, in a preferred embodiment the first pair of opposed faces of the spool are of equal effective area, the second pair of opposed faces of the spool each have an effective area less than the effective area of one of the first pair of opposed faces, and the pair of opposed faces of the piston are of equal effective area; the arrangement being such that, to reverse the spool, fluid pressure is caused to be admitted to the said other spool-biasing chamber in opposition to the load

on the spool applied by fluid pressure in said one spool-working chamber and fluid pressure in both spool-working chambers is caused to be equalized.

The sequence of fluid pressurization and exhausting of the 5 spool chambers to achieve reversal of the spool may conveniently follow either of two courses. In a first and preferred arrangement, with the spool at an end of its stroke, one spool-working chamber is open to fluid pressure while the other spool-working chamber is open to exhaust to urge the spool to that end and one spool-biasing chamber is open to exhaust, fluid pressure is first caused to be admitted during axial movement of the piston to the other spool-biasing chamber in opposition to the load on the spool applied by fluid pressure in said one spool-working chamber and thereafter, at or towards 10 the end of stroke of the piston consistent with its axial movement, fluid pressure in both spool-working chambers is caused to apply equal and opposite axial thrusts on the spool to cause the spool to reverse. By a further arrangement, with the spool at an end of its stroke, one spool-working chamber is open to fluid pressure while the other spool-working chamber is open to exhaust to urge the spool to that end and one spool-biasing chamber is open to exhaust, during axial movement of the piston, fluid pressure in both spool-working chambers is first 15 caused to apply equal and opposite axial thrusts on the spool and thereafter, at or towards the end of stroke of the piston consistent with its axial movement, fluid pressure is caused to be admitted to the other spool-biasing chamber in opposition to the load on the spool applied by fluid pressure in said one spool-working chamber to reverse the spool.

Preferably each of the pair of piston chambers is respectively 20 in constant communication with one of the pair of spool-working chambers and each piston chamber has associated therewith a port through which it is adapted to be exhausted.

25 During axial movement of the piston, the port through which the contracting piston chamber is exhausting is adapted to be closed by the piston towards its end of stroke and thereafter fluid pressure in the contracting piston chamber and spool-working chamber in communication therewith applies an axial 30 thrust to the spool which equalizes the opposing axial thrust applied to the spool by fluid pressure in the expanding piston chamber and spool-working chamber in communication therewith. By having the first pair of opposed faces of the spool of equal effective area, the second pair of opposed faces 35 of the spool of equal effective area, and the pair of opposed faces of the piston of equal effective area, when the port through which the contracting piston chamber is exhausting is closed by axial movement of the piston, it will be apparent that 40 fluid pressure in both spool-working chambers and piston chambers is at least equalized by equal and opposite reaction through the piston. However, it should be borne in mind that the inertia of the moving piston may impart a pressure impulse to fluid in the contracting piston chamber when the port through which it is exhausting is closed thereby imparting a 45 momentarily higher fluid pressure in the contracting piston chamber and spool-working chamber in communication therewith than the fluid pressure in the other piston chamber and spool-working chamber. As such, when using relatively 50 heavy piston, it is preferable that the "equalization" of fluid pressure in the spool-working chambers (or thrust on the spool in both axial directions) causes the spool to reverse so that the pressure impulse developed by loss of inertia of the piston at the end of its stroke imparts a "kick" to the spool to 55 lift it from its end of stroke position.

60 Although fluid pressure in both spool-working chambers to apply equal and opposite axial thrusts on the spool may be achieved, as above described, by imparting an equal and opposite reaction through the piston to fluid in the piston chambers, when the port through which the contracting piston chamber exhausts is closed, it will be apparent that if the 65 piston is located at an extreme end of its stroke (for example when abutting the end of its cylinder) such equal and opposite reaction through the piston is not possible and the motor may stall. To avoid such a possibility, in addition or as an alterna- 70

tive to the provision of equal and opposite reaction through the piston, equal and opposite axial thrusts on the spool may be achieved by use of auxiliary valve means which is adapted to be actuated when the piston is located at or towards an end of stroke position. With the spool at an end of stroke position, actuation of the auxiliary valve means admits fluid pressure to the spool-working chamber which when pressurized, urges the spool to its other end of stroke position. Preferably such auxiliary valve means is adapted to be actuated during axial movement of the piston to admit fluid pressure to the respective spool-working chamber only when the piston is located at a position in which the port through which the contracting piston chamber exhausts is closed by the piston and prior to the piston abutting the end of its cylinder. The auxiliary valve means conveniently comprises ports in the piston cylinder which are adapted to communicate with fluid pressure and are controlled by cooperating lands on the piston (or piston rod) so that when the piston is at one or other extreme end of its stroke a port in communication with fluid pressure is opened to communicate with the respective spool-working chamber.

In a preferred embodiment, with the motor in a condition in which the spool is located at an end of its stroke, one spool-working chamber open to fluid pressure, the other spool-working chamber open to exhaust and one spool-biasing chamber open to exhaust, fluid pressure is caused to be admitted to the other spool-biasing chamber in opposition to the load on the spool applied by fluid pressure in said one spool-working chamber by way of valve means responsive to axial movement of the piston. In the aforementioned construction of the motor in which a port through which the contracting piston chamber exhausts is closed by the piston during its axial movement, the valve means is preferably adapted to be actuated to admit fluid pressure to the said other spool biasing chamber immediately before the port through which the contracting piston chamber exhausts is closed by the piston; consequently, when the valve means is actuated, the spool will subsequently reverse on fluid pressure in both spool-working chambers being caused to apply equal and opposite axial thrusts on the spool. Alternatively the valve means may be arranged to be actuated to admit fluid pressure to the said other spool-biasing chamber to cause the spool to reverse after fluid pressure in both spool-working chambers has applied equal and opposite axial thrust on the spool. Conveniently the valve means comprises cooperating ports and land between the piston and its cylinder or between a piston rod and bore through which it is slidable.

In a further embodiment, with the motor in a condition in which the spool is located at an end of its stroke, one spool-working chamber open to fluid pressure, the other spool-working chamber open to exhaust and one spool-biasing chamber open to exhaust, fluid pressure is caused to be admitted to the other spool-biasing chamber in opposition to the load applied by fluid pressure in said one spool-working chamber by way of bleed passage means which is in constant communication with said other spool-biasing chamber and is adapted to communicate with fluid pressure during expansion of a piston chamber consistent with the spool at said end and to communicate with exhaust during contraction of a piston chamber consistent with the spool at the other end of its stroke.

Two control ports may be provided in the spool cylinder each of which is adapted to respectively communicate with one of the pair of spool-biasing chambers. The control ports are controlled by reciprocation of the spool to be alternately opened and closed to their respective spool-biasing chambers and, with the spool at an end of its stroke, one control port is open and the other control port is closed to its respective spool-biasing chamber, the closed control port being associated with the spool-biasing chamber which, if subjected to fluid pressure, would urge the spool away from its said end of stroke position. The control ports are adapted to communicate alternately with fluid pressure and exhaust during reciprocation of the piston so that, with the spool at an end of

its stroke, when the piston reaches an end of its stroke consistent with the spool in said end of stroke position, the closed control port communicates with fluid pressure and the open control port (and thereby its respective spool-biasing chamber) communicates with exhaust. Upon reversal of the spool, initial movement of the spool from its end of stroke position causes the control port in communication with fluid pressure to be opened to its respective spool-biasing chamber to urge the spool to its other end of stroke position. Conveniently the aforementioned valve means is adapted to control communication between each control port and its respectively associated spool-biasing chamber so that, when a control port is open to fluid pressure, actuation of said valve means causes communication to be made between said control port and its respective spool-biasing chamber. Alternatively the aforementioned bleed passage means may comprise small bleed passages which are in constant communication between each control port and its respectively associated spool biasing chamber.

It may be possible for the motor to be assembled or come to rest in a position in which both the spool-working chambers, biasing chambers and the piston chambers communicate with fluid pressure. If the first pair of spool faces are of equal effective area, the second pair of spool faces are of equal effective area and the pair of opposed piston faces are of equal effective area it will be apparent that in such condition hydraulic equilibrium may result on the spool which could cause the motor to stall. To avoid such a possibility the second pair of opposed spool faces are preferably made with different effective areas and consequently even if each of the spool working and biasing chambers communicate with fluid pressure the spool will be biased to one or other end position of its stroke.

Two embodiments of the present invention will now be described, by way of example only, with reference to the accompanying illustrative drawings in which:

FIG. 1 shows a fluid pressure operated motor constructed in accordance with the present invention and in part section taken along the longitudinal axis of the spool and piston, and

FIG. 2 illustrates a further, and preferred embodiment of the invention.

Referring firstly to FIG. 1, the motor includes a body part 1 which defines a spool cylinder shown generally at 2 and a body part 1a which defines a piston cylinder 3. The spool cylinder 2 is stepped to provide end parts 4 and 4a of equal diameter and adjacent midparts 5 and 6. Spool cylinder part 4 communicates with part 5 and cylinder part 5 is of larger diameter than cylinder part 4. Spool cylinder part 4a communicates with cylinder part 6 and cylinder part 6 is of larger diameter than cylinder part 5. Axially slidably in the spool cylinder 2 is a spool shown generally at 7 which comprises end lands 8 and 9 which are respectively slidable in cylinder end parts 4 and 4a and lands 10 and 11 which are respectively slidable in cylinder parts 5 and 6. One end of the spool 7 is provided with a rod 12 and the end of the spool cylinder 2 remote from the rod 12 is provided with an abutment 13. The end face of the spool 7 adjacent the rod 12 defines with its adjacent end of the spool cylinder part 4 a spool-working chamber 12a and the opposite end face of the spool 7 (adjacent the abutment 13) defines with its adjacent end of the spool cylinder part 4a a second spool-working chamber 13a. The rod 12 and abutment 13 provide physical limits to axial movement of the spool in its cylinder and may be castellated to ensure that fluid under pressure can flow over the ends of the spool when it is located at one or other end of its stroke in the spool cylinder. In fact, in the embodiment described, the physical limitation of stroke is only precautionary, since the hydraulic operation is so arranged that the stroke is limited hydraulically.

The spool land 10 has a side face 14 which is located adjacent the spool land 8 and partly defines with the adjacent stepped end of the cylinder part 5 a spool-biasing chamber 15. Similarly, the spool land 11 has a side face 16 which is located adjacent the spool land 9 and partly defines with the adjacent stepped end of the cylinder part 6 a further spool-biasing

chamber 17. The spool lands 10 and 11 have opposed side faces 18 and 19 respectively which define, with the adjacent ends of cylinder parts 5 and 6, a spool transfer chamber 20.

Slidably housed in the piston cylinder 3 is a piston shown generally at 21 having rods 21a extending axially and in sealed manner through bores 21b in the end walls of the body part 1a and a pair of axially spaced lands 22 and 23. Defined between the opposed side faces of the lands 22 and 23 and part length of the piston cylinder 3 is a piston transfer chamber 24; defined between the piston land 22 and one end part of the piston cylinder 3 is a first piston chamber 25; and defined between the piston land 23 and the other end part of the piston cylinder 3 is a second piston chamber 26. An annular recess 27 is provided in the piston rod 21a adjacent the piston land 22 and on the side thereof in the chamber 25; similarly a further annular recess 28 is provided in the piston rod 21a adjacent the piston land 23 and on the side thereof in the chamber 26. The annular recesses 27 and 28 are so arranged that in the unlikely event of the piston 21 being located at one or other extreme end of its stroke (which is ultimately determined by the piston lands 22 and 23 abutting their respective ends of the piston cylinder 3) the annular recess 27 will be in communication with a port 30 in the bore 21b or the annular recess 28 will be in communication with a port 31 in the bore 21b. Normally the ports 30 and 31 are closed by the full diameter of the piston rods 21a.

The motor is provided with an inlet port 32 which is adapted to be connected to a source of fluid (preferably hydraulic) under pressure. The inlet port 32 communicates through passage 33 with the port 30 in the bore 21b; through passage 34 with the port 31 in the bore 21b; through a passage 35 with a pressure inlet port 36 which is located in the spool cylinder part 4; and also by way of a branch passage 37 with a pressure inlet port 38 which is located in the spool cylinder part 4a. .

The ports 36 and 38 are so located that, at one end of stroke of the spool 7, the port 36 is closed by the spool land 8 whilst the port 38 communicates with the spool-working chamber 13a; at the other end of stroke of the spool, the port 36 communicates with the spool working chamber 12a while the port 38 is closed by the spool land 9, and in no position of the spool are both ports 36 and 38 simultaneously closed by spool lands 8 and 9 to the spool-working chambers 12a and 13a respectively.

Located in the spool cylinder part 4 to be in permanent communication with the spool chamber 12a is a port 41 which communicates through a passage 42 with a port 43 opening into the piston chamber 25 at one end of the piston cylinder 3. Located in the spool cylinder part 4a to be in permanent communication with the spool chamber 13a is a port 44 which communicates through a passage 45 with a port 46 opening into the piston chamber 26 at the end of the piston cylinder 3 remote from the port 43.

The motor is provided with an exhaust port 47 which communicates through a port 48 with the spool cylinder 2. The port 48 is located to be in constant communication with the spool transfer chamber 20. Also located in the spool cylinder 2 to be in permanent communication with the transfer chamber 20 is a port 49 which communicates through a passage 50 with a port 51 in the piston cylinder 3. The port 51 is positioned intermediate the ports 43 and 46 and is located to be in permanent communication with the piston transfer chamber 24.

Located in and towards the end of the spool cylinder part 5 adjacent the spool cylinder part 4 is a control port 52 which communicates through a passage 53 with a port 54 located in the piston cylinder 3 between the ports 51 and 46. Located in and towards the end of the spool cylinder part 6 adjacent the spool cylinder part 4a is a further control port 55 which communicates through a passage 56 with a port 57 located in the piston cylinder 3 between the ports 51 and 43.

The control port 52 is controlled by the spool land 10 and the control port 55 is controlled by the spool land 11; the spool lands 10, 11 and control ports 52, 55, are so arranged

that, at one end of stroke of the spool, the control port 52 is closed by the spool land 10 and the control port 55 communicates with the spool-biasing chamber 17; at the other end of stroke of the spool, the control port 55 is closed by the spool land 11 and the control port 52 communicates with the spool-biasing chamber 15; and in no position of the spool are both control ports 52 and 55 simultaneously closed by the lands 10 and 11 to the spool-biasing chambers 15 and 17 respectively.

The spool cylinder has a port 58 which is situated in the spool cylinder part 5 and is located between the ports 49 and 52; the port 58 communicates through a passage 59 with a port 60 in the piston cylinder 3, the port 60 being located between the ports 57 and 43 and towards the port 43. Provided in the spool cylinder part 6 is a port 61 which is located between the ports 49 and 55 and communicates through a passage 62 with a port 63 in the piston cylinder 3, the port 63 being located between the ports 54 and 46 and towards the port 46. Ports 58 and 61 are controlled to be opened and closed to communication with the transfer chamber 20 by spool lands 10 and 11 respectively. The spool lands 10, 11 and ports 58, 61 are so arranged that, at one end of stroke of the spool, the port 58 communicates with the transfer chamber 20 while the port 61 is closed by the spool land 11; at the other end of stroke of the spool, the port 61 communicates with the transfer chamber 20 while the port 58 is closed by the spool land 10; and in no position of the spool do both ports 58 and 61 simultaneously communicate with the transfer chamber 20. The spool lands 9, 11 and ports 38, 61 are so arranged that when port 38 is open to chamber 13a port 61 is closed by land 11, when port 61 is open to chamber 20 port 38 is closed by land 9, and in no position of the spool do both ports 38 and 61 simultaneously communicate with chambers 13a and 20 respectively. Similarly the spool lands 8, 10 and ports 36, 58 are so arranged that when port 36 is open to chamber 12a port 58 is closed by land 10, when port 58 is open to chamber 20 port 36 is closed by land 8, and in no position of the spool do both ports 36 and 58 simultaneously communicate with chambers 12a and 20 respectively.

Provided in the motor are two small bleed passages 64 and 66 of which bleed passage 64 is in constant communication, at one end with the spool-biasing chamber 15, and at its other end with the passage 53; and bleed passage 65 is in constant communication, at one end with the spool-biasing chamber 17, and at its other end with the passage 56. The bleed passages 64 and 65 provide means whereby, when fluid under pressure is present in one or other of the passages 53 and 56, fluid can always seep into one or other of the spool-biasing chambers 15 and 17. Although, in the present embodiment the bleed passages 64 and 65 are shown as being formed by conduits in the body part 1, they can be provided by suitable machining or porting of the spool lands 10 and 11 respectively or by machining the spool cylinder parts 5 and 6 to predetermined tolerances to provide the required seepage from the ports 52 and 55 to the spool-biasing chambers 15 and 17 respectively.

The various diameters of the spool 7 are so arranged that the effective area at the end of the spool in the spool chamber 12a is equal to the effective area at the end of the spool in the spool chamber 13a; the effective pressure area of the spool side face 14 in the spool-biasing chamber 15 (which, if the chamber 15 contained fluid under pressure would cause the spool to be biased rightwardly in the drawing) is slightly less than the effective area of the spool side face 16 in the spool-biasing chamber 17 (which, if the chamber 17 contained fluid under pressure would bias the spool leftwardly in the drawing); and the effective area of the side face 16 in the spool-biasing chamber 17 is slightly less than the effective area of the end of the spool in either chambers 12a or 13a.

The ports 43 and 46 in the piston cylinder 3 are so arranged that when the piston 21 is located at one or other end of its cylinder (i.e., when the side face of land 22 abuts the end of the piston cylinder 3 or the side face of land 23 abuts the other end of the piston cylinder), the port 43 or 47 which is adjacent

the end of the piston cylinder against which the piston abuts, communicates by way of annular recess 27 or 28 with its adjacent port 30 or 31 (and thereby the inlet port). To ensure that such communication is achieved, the port 43 is partly formed by a recess 43a in the body part 1a and the port 46 is partly formed by a recess 46a in the body part 1a.

The annular recesses 27 and 28 in the piston rods 21a are arranged so that immediately before and when the piston abuts one or other end of its cylinder, the annular recess 27 or 28 enters the bore 21b and the port 43 or 46 communicates with the fluid inlet port 32 respectively by way of recess 43a or 46a, annular recess 27 or 28, port 30 or 31 and passage 33 or 34.

The piston lands 22 and 23 are arranged with respect to the ports in the piston cylinder 3 so that at or towards one end of stroke of the piston, the ports 57 and 60 communicate with the piston transfer chamber 24 and the ports 54 and 63 communicate with the piston chamber 26; at or towards the other end of stroke of the piston the ports 54 and 63 communicate with the transfer chamber 24 and ports 57 and 60 communicate with the piston chamber 25; in no position of the piston is either port 43 or port 46 in communication with the transfer chamber 24; and in no position of the piston are both ports 54 and 57 either simultaneously closed by the piston lands 2 and 23 respectively or open to communicate with the piston transfer chamber 24.

We will now consider a cycle of operation of the motor above described and illustrated with reference to FIG. 1. Assume that the motor is assembled in the position drawn, that the inlet port 32 is connected to a source of hydraulic fluid under pressure and that the exhaust port 47 is connected to a fluid reservoir.

Passages 32 to 35 and 37 always contain fluid under pressure and, in the position of the motor illustrated with both the spool and piston respectively at and towards one end of their respective strokes, spool chamber 12a communicates with fluid under pressure by way of port 41, passage 42, port 43 and annular recess 27 and port 30 to the passage 33; spool chamber 13a communicates with fluid under pressure by way of port 38 and passage 37. Consequently the piston chamber 26 is open to fluid pressure by way of port 46, passage 45 and port 44 which is in permanent communication with spool chamber 13a. As the spool 7 is at one end position of its stroke, ports 52 and 61 are closed by the spool lands 10 and 11 respectively but these ports communicate by way of passages 53 and 62 with the piston chamber 26 and thereby with fluid under pressure. Spool-biasing chamber 17 communicates with exhaust by way of port 55, passage 56, port 57 and the piston transfer chamber 24 (which is always open to exhaust) while port 60 can communicate with exhaust by way of passage 59 and port 58 which is open to the spool transfer chamber 20 (which is always open to exhaust).

As the effective end areas of the spool in the chambers 12a and 13a are equal and both chambers 12a and 13a communicate with fluid under pressure and also as the effective areas of the piston lands 22, 23 in piston chambers 25, 26 respectively are equal and both piston chambers 25 and 26 communicate with fluid under pressure it would appear that the motor is in a stalled condition. However, fluid pressure in the passage 53 bleeds into the spool-biasing chamber 15 by way of bleed passage 64 and as the spool-biasing chamber 17 is open to exhaust and the combined effective area of the spool in the chambers 12a and 15 is larger than the effective area of the spool in the chamber 13a the spool is lifted from its end seat position as illustrated and commences to move in the direction of arrow A.

During movement of the spool in the direction of arrow A, control port 52 is opened to the spool-biasing chamber 15 to move the spool to the other end of its stroke. By movement of the spool in the direction of arrow A, port 58 is closed to the spool transfer chamber 20 by spool land 10 and immediately thereafter the port 36 is opened by the spool land 8 to spool chamber 12a; port 38 is closed by the spool land 9 immediate-

ly prior to port 61 being opened by the spool land 11 to communication with the spool transfer chamber 20. As the control port 52 is being opened to the spool-biasing chamber 15 by spool land 10, control port 55 is being closed to the spool-biasing chamber 17 by spool land 11 and when the spool is located at its end position in the direction of arrow A, control port 52 is fully open to chamber 15 and control port 55 is closed by land 11.

With the spool at the end of its stroke in the direction of arrow A, port 38 is closed by spool land 9 and consequently spool chamber 13a and passage 45 are not open to fluid under pressure and the piston chamber 26 communicates with exhaust by way of port 63, passage 62 and port 61 which is open to the spool transfer chamber 20, and the spool-biasing chamber 15 communicates with exhaust by way of control port 52, passage 53 and the piston chamber 26. The piston chamber 25 communicates directly with fluid pressure by way of port 43, passage 42, chamber 12a and port 36 and consequently the piston moves in the direction of arrow A which movement commences when port 61 opens to chamber 20.

During initial movement of the piston 21 in direction of arrow A the port 30 is closed by the full diameter of the piston rod 21a and thereafter the port 60 is closed by the piston land 22 and reopened to the piston chamber 25 and thereby fluid under pressure (however, since the port 58 of passage 59 is closed by the spool land 10 this is without effect). Continued movement of the piston causes piston land 22 to close port 57 and reopen it to the piston chamber 25 and thereby fluid pressure and thereafter causes piston land 23 to close port 54 and reopen it to the piston transfer chamber 24 and thereby exhaust, consequently the passage 56 now contains fluid under pressure and the spool-biasing chamber 15 communicates through port 52, passage 53 and piston transfer chamber 24 with exhaust. Further movement of the piston causes the piston land 23 to close port 63 from the piston chamber 26 and reopen it to the piston transfer chamber 24 and thereby exhaust. When port 63 is closed by piston land 23 the piston chamber 26 is closed to exhaust, and the fluid pressure in spool chamber 13a, passage 45 and piston chamber 26 is equalized (by equal and opposite reaction) with fluid pressure in the piston chamber 25 to reverse the spool as described hereafter. The fluid in passage 45 may be subjected to a pressure impulse by the inertia of the piston. Since the spool chamber 12a is open to fluid pressure (by way of port 36), the spool-biasing chamber 15 is open to exhaust (by way of piston transfer chamber 24) and the spool-biasing chamber 17 contains fluid under pressure (by way of the bleed passage 65 from the passage 56), the fluid pressure in piston chamber 26 (generated by the piston 21 being arrested at the end of its stroke in the direction of arrow A together with the pressure applied through the piston from the fluid in piston chamber 25 to equalize the pressure in the piston chambers 25 and 26) causes the spool to move in the direction of arrow B.

During the movement of the spool 7 in the direction of arrow B, the spool land 11 opens control port 55 to communication with the spool-biasing chamber 17 and the port 61 is closed by the spool land 11 immediately prior to the port 38 being opened to the spool chamber 13a by the spool land 9. As port 38 is being opened by spool land 9, port 36 is being closed by spool land 8. Port 36 is closed by spool land 8 immediately before port 58 is opened to transfer chamber 20 and the spool moves to the end of its stroke in the direction of arrow B as illustrated.

The piston chamber 26 now communicates with fluid pressure by way of port 46 and passage 45 to chamber 13a while the piston chamber 25 communicates with exhaust by way of port 60, passage 59, port 58 and the spool transfer chamber 20 so that the piston reverses and moves in the direction of arrow B, such movement commencing when port 58 opens to chamber 20. Port 54 communicates with the piston transfer chamber 24 (and spool-biasing chamber 15 is consequently open to exhaust by way of the bleed passage 64) while the port 57 communicates with the piston chamber 25 and thereby exhaust.

Continued movement of the piston in the direction of arrow B causes piston land 23 to close port 63 to the piston transfer chamber 24 and reopen it to the piston chamber 26 (which is without effect since the port 61 is closed by the spool land 11). Further movement of the piston causes the piston land 23 to close port 54 to the piston transfer chamber 24 and reopen it to the piston chamber 26 and thereby fluid under pressure. Fluid under pressure now bleeds into the spool-biasing chamber 15 by way of the bleed passage 64; however, as the effective area of the spool face 14 in the chamber 15 is less than the effective area of the spool end face in the chamber 13a and the piston chamber 25 (and thereby the spool chamber 12a and spool-biasing chamber 17) is open to exhaust, the position of the spool remains unchanged. Still further movement of the piston causes the piston land 22 to close the port 57 to the piston chamber 25 and reopen it to the piston transfer chamber 24 and thereby exhaust.

Towards the end of stroke of the piston in the direction of arrow B, the piston land 22 closes port 60 and thereby the piston chamber 25 is cutoff from exhaust. As soon as the port 60 is closed by the piston land 22 from the chamber 25, the fluid pressure in the chamber 25, passage 42 and spool chamber 12a acts to reverse the spool as described hereafter. The pressure in piston chamber 25 is equalized to the fluid pressure in the chamber 26 (by equal and opposite reaction through the piston 21) and consequently the resultant pressure on the spool 7 in the spool chamber 12a and the spool-biasing chamber 15 (together with the pressure impulse in spool chamber 12a developed by the loss in inertia of the piston) overcomes the opposing pressure on the spool in the chamber 13a and the spool is lifted from its end position and moved in the direction of arrow A and the motor commences a further cycle of reciprocation.

It is possible that during operation or assembly of the motor a condition can occur in which the piston is located at an extreme end of its stroke (i.e., when one of the piston lands 22, 23, abuts an end of the piston cylinder and the associated port 60, 63 is closed to its associated piston chamber 25, 26, then it will be apparent that fluid pressure in the piston chambers 25 and 26 cannot be equalized. In such a condition, although one or other of the spool-biasing chambers 15, 17 will contain fluid under pressure and act in a sense to reverse the spool, if both the spool chambers 12a and 13a do not contain fluid at the same pressure then the spool will not reverse and the motor will stall. To ensure that the motor will not stall with the piston at an extreme end of its stroke the passages 33 and 34 and respective ports 30 and 31 are provided which are adapted to communicate with the annular recesses 27 and 28 in the piston rod 21a when the piston is at or towards one or other extreme ends of its stroke (that is after one or other of the ports 60, 63 has been closed to its respective piston chamber 25, 26). If a condition now arises in which the piston is at an extreme end of its stroke, say in the direction of arrow B in the drawing, fluid under pressure in the passage 33 can now communicate through port 30, annular recess 27, recess 43a of port 43 and passage 42 with the chamber 12a so that the fluid pressure in chambers 12a and 13a is equalized and the spool is moved in the direction of arrow A by the effect of fluid pressure in spool-biasing chamber 15. Similarly, when the piston is located at the extreme end of its stroke in the direction of arrow A, fluid under pressure passes through the port 31, annular recess 28, recess 46a of port 46 and passage 45 to the chamber 13a to equalize pressure in the chambers 12a and 13a so that fluid pressure in the spool-biasing chamber 17 causes the spool to reverse and move in the direction of arrow B.

The cooperation between the annular recesses 27, 28, in the piston rod and associated ports 30, 31, effectively constitute valves and can be replaced by alternative types of valves as will be apparent to persons skilled in the art and which are automatically actuated to equalize fluid pressure in the spool-working chambers 12a, 13a in the event of the piston 21 coming to rest at, or being assembled in, one or other extreme ends of its stroke (when the piston land 22 or 23 abuts the end of the piston cylinder).

The spool lands 8 to 11 are conveniently provided with annular recesses 8a to 11a respectively which recesses are located so that, when their respective land closes a port containing fluid pressure, the port in question communicates with the recess and fluid pressure on the spool from the port is equalized around the spool thereby maintaining the spool in balance in its cylinder. In no position of the spool do any of the annular recesses 8a to 11a bridge two or more ports in the spool cylinder.

In the above described embodiment illustrated with reference to FIG. 1, it is seen that for reversal of the spool 7 from one end of its stroke to the other it is necessary for fluid under pressure to be present in either the spool-biasing chamber 15 or chamber 17 and for the fluid pressure in chambers 12a and 13a to be equalized. As described, fluid under pressure can enter the spool-biasing chambers 15 and 17 either by controlled seepage from the ports 52 and 55 respectively or by way of bleed passages 64 and 65 respectively. By so pressurizing the spool-biasing chambers it is possible, when the piston is reciprocating at high speed, for a back pressure to build up in one or other of the spool chambers 12a, 13a which back pressure, together with pressure in the adjacent spool-biasing chamber, could result in the spool reversing prematurely and thereby cause a short stroke for the piston. For example, with the piston moving at high speed in the direction of arrow B and the spool in the position shown in FIG. 1, with the passage 53 (and thereby the spool-biasing chamber 15 by way of passage 64) communicating with fluid pressure in piston chamber 26 it is possible, even with the piston chamber 25 open to exhaust by way of port 60, passage 59, and spool transfer chamber 20, for back pressure to build up in chamber 12a by way of passage 42 and port 43. The combined force resulting from the back pressure and from pressure in spool-biasing chamber 15 could be greater than the force resulting from the pressure in spool chamber 13a and in such case the spool would reverse prematurely and thereby cause the piston to reverse prematurely. Such premature reversal of the spool is unlikely to occur when the piston is reciprocating at slow speeds but it is possible during high-speed reciprocation of the piston and the piston could, as a consequence, exhibit short stroking. The possibility of such short stroking of the piston is generally undesirable and a preferred embodiment of the present invention will now be described with reference to FIG. 2, in which the possibility of premature reversal of the spool and thereby short stroking of the piston is minimized.

For convenience of description, the same parts or members of the motor illustrated in FIG. 2 to those above described and illustrated with reference to FIG. 1 have been accorded the same references.

In FIG. 2 the bleed passages 64, 65 are omitted and the spool-biasing chambers are not intended to be pressurized either by controlled seepage or otherwise directly from the passages 53, 56. Similarly the ports 30 and 31 and their respective passages 33 and 34 are omitted and the ends of the piston cylinder 3 are recessed at 66 so that the port 43 is in constant communication with piston chamber 25 and the port 46 is in constant communication with piston chamber 26 even when the piston is located at one or other extreme end of its stroke (that is when piston land 22 or 23 abuts the adjacent end of the piston cylinder).

Located in the spool cylinder part 4 is a signalling port 67 which communicates with the spool-biasing chamber 15 when the spool is located at the end of its stroke in the direction of arrow B and similarly located in the spool cylinder part 4a is a further signalling port 68 which communicates with the spool-biasing chamber 17 when the spool is located at the end of its stroke in the direction of arrow A. The port 67 communicates with the chamber 15 by way of an annular recess 69 in the spool 7 and the port 68 communicates with the chamber 17 by way of an annular recess 70 in the spool 7. The ports 67, 68 and recesses 69, 70 are so located with respect to the ports 52 and 55 that, when the spool moves rightwardly from the end of its stroke and in the direction of arrow A, the signalling port 67 maintains communication with the spool-biasing chamber

15 until the port 52 is opened by the spool land 10 to communication with the spool-biasing chamber 15, after which the signalling port 67 is closed by the spool land 8 and, when the spool moves leftwardly from the end of its stroke and in the direction of arrow B, the signalling port 68 maintains communication with the spool-biasing chamber 17 until the port 55 is opened by the spool land 11 to communication with the spool-biasing chamber 17, after which the signalling port 68 is closed by the spool land 9.

The signalling port 67 communicates through a passage 71 with a port 72 in the bore 21b of the body part 34 1a at the end of the piston cylinder adjacent the port 43. Similarly the signalling port 68 communicates through a passage 73 with a port 74 in the bore 21b of the body part 1a at the end of the piston cylinder adjacent the port 46. Located in the bore 21b diametrically opposite (or in the same diametral plane as) the port 72 is a port 75 which communicates by way of a passage 76 with the passage 53 and thereby with the ports 52 and 54. Similarly located in the bore 21b diametrically opposite (or in the same diametral plane as) the port 74 is a port 77 which communicates by way of a passage 78 with the passage 56 and thereby with the ports 55 and 57.

The ports 72 and 75 are so positioned in the bore 21b that, as the piston 21 moves in the direction of arrow B, they are caused to communicate with each other by way of the annular recess 27 in the piston rod 21a immediately before the port 60 is closed by the piston land 22 and thereafter are maintained in communication through the recess 27 until the piston land 22 abuts the end of the piston cylinder 3 at the end of stroke of the piston in the direction of arrow B.

As the piston land 22 approaches, and immediately before it abuts, the end of the piston cylinder, a normally closed small port 79 in the bore 21b is opened to the recess 27 so that at the limit of stroke of the piston in the direction of arrow B the ports 72, 75, and 79 are in communication by way of recess 27. Similarly the ports 74 and 77 are so positioned in the bore 21b that, as the piston 21 moves in the direction of arrow A, they are caused to communicate with each other by way of the annular recess 28 in the piston rod 21a immediately before the port 63 is closed by the piston land 23 and thereafter are maintained in communication through the recess 28 until the piston land 23 abuts the end of the piston cylinder 3. As the piston land 23 approaches, and immediately before it abuts the end of the piston cylinder, a normally closed small port 81 in the bore 21b is opened to the recess 28 so that at the limit of stroke of the piston in the direction of arrow A, the ports 74, 77 and 81 are in communication by way of recess 28.

The port 79 in the bore 21b is in permanent communication with the piston chamber 25 by way of a passage 80 and similarly the port 81 is in permanent communication with the piston chamber 26 by way of a passage 82.

It is to be noted in FIG. 2 that the annular recesses 27 and 28 are axially spaced from their adjacent piston lands and are so arranged that recess 27 cannot communicate directly between the ports 72, 75, and the piston chamber 25, and recess 28 cannot communicate directly between the ports 74, 77 and the piston chamber 26.

We will now consider a cycle of operation of the motor above described and illustrated with reference to FIG. 2. Assume that the motor is assembled in the position drawn, that the inlet port 32 is connected to a source of hydraulic fluid under pressure and that the exhaust port 47 is connected to a fluid reservoir.

Passages 32, 35 and 37 always contain fluid under pressure and, in the position of the motor illustrated with both the spool and piston respectively at, and approaching one end of their respective strokes, spool chamber 13a communicates with fluid under pressure by way of port 38 and the spool chamber 12a communicates with exhaust by way of port 41, passage 42, piston chamber 25, port 60, passage 59, spool transfer chamber 20 and passage 47 so that the spool is held at the end of its stroke in the direction of arrow B, while the piston chamber 26 communicates with fluid pressure by way of 75

passage 45 and spool chamber 13a and the piston chamber 25 communicates with exhaust by way of port 60, passage 59, spool transfer chamber 20 and passage 47 so that the piston is moving in the direction of arrow B.

5 The piston is shown with its land 23 opening port 54 to communication with piston chamber 26 (which is without effect since the ports 52 and 75 are closed by spool land 10 and piston rod 21a respectively). Further movement of the piston causes the piston land 22 to close the port 57 to the piston chamber 25 and reopen it to the piston transfer chamber 24 and thereby exhaust.

Towards the end of stroke of the piston in the direction of arrow B, the ports 72 and 75 are placed in communication through the piston recess 27 immediately before the piston land 22 closes port 60 and consequently the spool-biasing chamber 15 communicates with fluid pressure by way of signalling port 67, passage 71, recess 27, port 75, passages 76 and 53, port 54 and piston chamber 26. However, since the effective area of the spool face 14 in the spool-biasing chamber 15 is less than the effective area of the spool end face in the spool-working chamber 13a and the piston chamber 25 (and thereby the spool-biasing chamber 12a) is open to exhaust, the position of the spool remains unchanged. As soon as the port 60 is closed by the piston land 22 from the chamber 25, the chamber 25 is cut off from exhaust. Fluid pressure in piston chamber 25, passage 42 and spool chamber 12a is equalized to the fluid pressure in the piston chamber 26 and spool chamber 13a and consequently the resultant pressure on the spool 7 in the spool chamber 12a and the spool biasing chamber 15 (by way of port 67) overcomes the opposing pressure on the spool in the working chamber 13a and the spool is lifted from its end position and moved in the direction of arrow A. On completion of reversal of the spool the piston 21 is hydraulically arrested.

During movement of the spool in the direction of arrow A, control port 52 is opened to the spool-biasing chamber 15, (prior to the signalling port 67 being closed by spool land 8) to move the spool to the other end of its stroke. By movement of the spool in the direction of arrow A, port 58 is closed to the spool transfer chamber 20 by spool land 10 and immediately thereafter the port 36 is opened by the spool land 8 to the spool-working chamber 12a; port 38 is closed by the spool land 9 immediately prior to port 61 being opened by the spool land 11 to communication with the spool transfer chamber 20 and signalling port 68 being opened to communication with the spool-biasing chamber 17 by way of spool recess 70. The ports 38 and 61 are located with respect to the spool lands 9 and 11 and the ports 36 and 52 are located with respect to the spool lands 8 and 10 so that in no position of the spool are both ports 38 and 61 simultaneously open from the spool lands 9 and 11 respectively and in no position of the spool are both ports 36 and 58 simultaneously open from the spool lands 8 and 10 respectively. As the control port 52 is being opened to the spool-biasing chamber 15 by spool land 10, control port 55 is being closed to the spool-biasing chamber 17 by spool land 11 and when the spool is located at its end of stroke position in the direction of arrow A control port 52 is fully open and control port 55 is closed.

With the spool at the end of its stroke in the direction of arrow A, port 38 is closed by spool land 9 and consequently spool-working chamber 13a and passage 45 are not open to fluid under pressure and the piston chamber 26 communicates with exhaust by way of port 63, passage 62 and port 61 which is open to the spool transfer chamber 20. The spool-biasing chamber 15 communicates with exhaust by way of control port 52, passage 53 and the piston chamber 26. The piston chamber 25 communicates with fluid pressure by way of port 43, passage 42, chamber 12a and port 36 and consequently the piston moves in the direction of arrow A.

During initial movement of the piston 21 in direction of arrow A the port 60 is closed by the piston land 22 from piston transfer chamber 24 and reopened to the piston chamber 25 and thereby fluid under pressure (however, since the port 58

of passage 59 is closed by the spool land 10, this is without effect. Continued movement of the piston in direction A causes piston land 22 to close port 57 and reopen it (and therethrough the passage 78) to the piston chamber 25 and thereby fluid pressure and thereafter causes piston land 23 to close port 54 and reopen it to the piston transfer chamber 24 and thereby exhaust. The passages 56 and 78 now contain fluid under pressure and the spool-biasing chamber 15 and passage 76 communicate with exhaust by way of through port 52, passage 53 and piston transfer chamber 24. Further movement of the piston causes the piston land 23 to close port 63 from the piston chamber 26 and reopen it to the piston transfer chamber 24 and thereby exhaust. However, immediately before the piston land 23 closes port 63, the ports 74 and 77 are placed in communication through the piston recess 28 and consequently the spool-biasing chamber 17 communicates with fluid pressure by way of signalling port 68, passage 73, port 74, recess 28, passages 78 and 56, port 57 and piston chamber 25. When port 63 is closed by piston land 23, fluid pressure developed in spool-working chamber 13a, passage 45 and piston chamber 26 acts to reverse the spool. The fluid in passage 45 is subjected to a pressure impulse (partly by the inertia of the piston). Since the spool-working chamber 12a is open to fluid pressure (by way of port 36), the spool-biasing chamber 15 is open to exhaust (by way of piston transfer chamber 24) and the spool-biasing chamber 17 contains fluid under pressure (by way of passages 73, 78, and 56), the pressure applied through the piston from fluid pressure in piston chamber 25 to equalize the pressures in the piston chambers 25 and 26 and also equalize the pressures in spool chambers 12a and 13a causes (by fluid pressure in the spool-biasing chamber 17) the spool to move in the direction of arrow B. On completion of reversal of the spool, the movement of the piston at the end of its stroke in the direction of the arrow A is arrested.

During movement of the spool 7 in the direction of arrow B, the spool land 11 opens control port 55 to communication with the spool-biasing chamber 17 immediately before the signalling port 68 is closed by spool land 9 and the port 61 is closed by the spool land 11 immediately prior to the port 38 being opened to the spool-working chamber 13a by the spool land 9. As port 38 is being opened by spool land 9, port 36 is being closed by spool land 8 until the spool reaches the end of its stroke in the direction of arrow B as illustrated in FIG. 2.

The piston chamber 26 now communicates with fluid pressure by way of port 46 and passage 45 to chamber 13a while the piston chamber 25 communicates with exhaust by way of port 60, passage 59, port 58 and the spool transfer chamber 20 so that the piston commences to move in the direction of arrow B. Port 54 communicates with the piston transfer chamber 24 and thereby exhaust while the port 57 communicates with the piston chamber 25 and thereby exhaust.

Further movement of the piston in the direction of arrow B causes the piston land 23 to close port 54 to piston transfer chamber 24 and reopen it to piston chamber 26 and thereby fluid under pressure is applied to the passages 53 and 76. Continued movement of the piston causes the piston land 22 to close port 57 to the piston chamber 25 and reopen it to the piston transfer chamber 24 which maintains passages 56 and 78 in communication with exhaust and the motor commences a further cycle of operation.

From the foregoing description with reference to FIG. 2, it will be seen that the alternate communication of the spool-biasing chambers 15 and 17 with fluid pressure is closely controlled by the position of the piston in its cylinder and that each spool-biasing chamber is only pressurized when the piston is located closely adjacent to its respective end of stroke position. Consequently the possibility of the piston exhibiting short stroking due to premature reversal of the spool is minimized. In effect the interaction between the ports 72, 75 and piston recess 27 (and similarly between the ports 74, 77 and piston recess 28) constitute an auxiliary valve which controls the timing at which the spool-biasing chamber 15

(and 17) is pressurized in readiness for the spool to reverse and as such may be replaced by other forms of valve means as will be apparent to persons skilled in the art (for example electrically controlled valves) which are responsive to the position of the piston in its cylinder so that the spool-biasing chamber 15 is automatically pressurized immediately prior to port 60 being closed during movement of the piston in the direction of arrow B and the spool-biasing chamber 17 is automatically pressurized immediately prior to port 63 being closed during movement of the piston in the direction of arrow A.

If a condition ever occurs during operation or assembly of the motor in which the piston is located at an extreme end of its stroke (i.e., when one of the piston lands 22, 23 abuts an end of the piston cylinder 3), then it will be apparent that fluid pressure in the piston chambers 25 and 26 cannot be equalized by equal and opposite reaction through the piston and in such a condition, although one or other of the spool-biasing chambers 15, 17 will contain fluid under pressure, if both the spool-working chambers 12a and 13a do not contain fluid at the same pressure then the spool will not reverse and the motor will stall. To ensure that such a condition cannot occur, the passages 80 and 82 and respective ports 79 and 81 are provided which are adapted to communicate with the annular recesses 27 and 28 in the piston rod 21a and through recesses 27 and 28 with ports 72, 75 and 74, 77 respectively when the piston is at or towards one or other extreme end of its stroke (that is after one or other ports 60, 63 has been closed to its respective piston chamber 25, 26 and the respective spool-biasing chamber (16, 17) have been opened to fluid pressure). If the condition now arises in which the piston is at an extreme end of its stroke, say in the direction of arrow B in the drawing, fluid under pressure in the passage 76 can now communicate through port 75, recess 27, port 79, passage 80, recess 66, port 43 and passage 42 with the chamber 12a so that fluid pressure in spool-working chambers 12a and 13a is equalized and the spool is moved in the direction of arrow A by the effect of fluid pressure in spool-biasing chamber 15. Similarly, when the piston is located at the extreme end of its stroke in the direction of arrow A, fluid under pressure in the passage 78 can now communicate through port 77, recess 28, port 81, passage 82, recess 66, port 46 and passage 45 to the chamber 13a to equalize fluid pressure in the spool-working chambers 12a and 13a so that fluid pressure in the spool-biasing chamber 17 causes the spool to reverse and move in the direction of arrow B.

The cooperation between the annular recesses 27, 28 and associated ports 75, 79, 77, 81 effectively constitute valves and can be replaced by alternative forms of valve means as will be apparent to persons skilled in the art and which are automatically actuated to equalize fluid pressure in the spool-working chambers 12a, 13a in the event of the piston 21 coming to rest at, or being assembled in, one or other extreme ends of its stroke.

In fluid pressure operated motors, a condition in which stalling is most likely to occur is that in which the piston and/or spool are located in their respective cylinders at the center of oscillation. In each of the above described embodiments assume that the piston 21 is located so that port 57 communicates with piston chamber 25 and port 54 communicates with piston chamber 26 (i.e., ports 54 and 57 are partly obturated by piston lands 23 and 22 respectively as shown in FIG. 2); that the spool 7 is located so that port 52 communicates with the spool-biasing chamber 15 and port 55 communicates with the spool-biasing chamber 17; that ports 36 and 38 are partly open to their respective spool-working chambers 12a, 13a and that ports 58 and 61 are closed by the spool lands 10 and 11 respectively. In such a condition the piston chamber 26 contains fluid under pressure by way of spool chamber 13a and passage 55 and consequently spool-biasing chamber 15 contains fluid under pressure, while spool-biasing chamber 17 communicates with the piston chamber 25 by way of port 55, passage 56 and partly open port 57 as does spool chamber 12a (which is open to fluid pressure) by way of

passage 42 and port 43. Consequently the pressure of fluid in the chambers 25, 26, 15, 17, 12a and 13a is equalized. However, since the areas of the spool end faces in chambers 12a and 13a are equal and the effective area on the spool side face 16 is slightly larger than the effective area on the spool side face 14, the spool is pressure biased and moves in the direction of arrow B to the end of its stroke and a stalled condition of the motor is thereby avoided.

In fluid pressure operated motors of the type in which reciprocation of a piston and spool mutually control the timing of reciprocation and reversal of each other, movement of the piston in its cylinder serves to actuate (or comprises) a valve by which fluid pressure has generally hitherto been directed from the fluid pressure source (usually a pump) to reverse the spool. By so doing part of the pressure output or volume from the pump is diverted from driving the piston to reversing the spool and consequently the piston tends to exhibit an appreciable decrease in its axial speed towards the ends of its stroke and possibly an appreciable reversal time. By a motor constructed in accordance with the present invention in which reversal of the spool is effected by fluid pressure in both spool-working chambers being caused to apply equal and opposite axial thrusts on the spool when the port (60 or 63) through which the contracting piston chamber exhausts is closed (by the piston land 22 or 23), the total output of the pump may be used to drive the piston for substantially the whole length of its stroke since no fluid pressure need be diverted from the pump to reverse the spool. Consequently the motor of the present invention may have minimal reversal time for its piston without appreciable slowing down of the piston towards the ends of its stroke. In the drawings (see FIG. 2) it would appear that, during reversal of the spool rightwardly from the position shown, fluid output is diverted from the pump or pressure inlet 32 by way of piston chamber 26, passages 53, 76 and 71, and control and signalling ports 52 and 67 into the spool-biasing chamber 15 to effect reversal of the spool. However, it must be borne in mind that the spool-working chamber 13a is contracting and the volume of fluid displaced therefrom may be arranged to be fractionally more than that entering the spool-biasing chamber 15 so that practically the total volume output from the pump is available for driving the piston.

I claim:

1. A fluid-pressure-operated motor for producing reciprocating motion which includes a spool axially slidable in a spool cylinder, the spool having a first pair of opposed faces each of which respectively communicates with one of a pair of spool-working chambers in the spool cylinder, and a second pair of opposed faces each of which respectively communicates with one of a pair of spool-biasing chambers in the spool cylinder; a piston axially slidable in a piston cylinder, the piston being double acting and having a pair of opposed faces each of which respectively communicates with one of a pair of piston chambers, reversal of the piston being initiated by reversal of the spool which serves to connect one piston chamber alternately to fluid pressure and to exhaust and to connect the other piston chamber alternately to exhaust and to fluid pressure respectively; and wherein the timing of reversal of the spool is determined according to the position of the piston in its cylinder, the arrangement being such that with the spool at an end of its stroke, one spool-working chamber is open to fluid pressure while the other spool-working chamber is open to exhaust to urge the spool to that end and one spool-biasing chamber is open to exhaust and, to reverse the spool, fluid pressure in both spool-working chambers is caused to apply equal and opposite axial thrusts on the spool and fluid pressure is caused to be admitted to the other spool-biasing chamber in opposition to the load on the spool applied by fluid pressure in said one spool-working chamber.

2. A motor as claimed in claim 1 in which the first pair of opposed faces of the spool are of equal effective area, the second pair of opposed faces of the spool each have an effective area less than the effective area of one of the first pair of opposed faces, and the pair of opposed faces of the piston are of equal effective area and wherein the arrangement is such that, to reverse the spool, fluid pressure is caused to be admitted to the other spool-biasing chamber in opposition to the load on the spool applied by fluid pressure in said one spool-working chamber and fluid pressure in both spool-working chambers is caused to be equalized.

3. A motor as claimed in claim 1 in which the arrangement is such that during axial movement of the piston fluid pressure is caused to be admitted to the said other spool-biasing chamber and thereafter, at or towards the end of stroke of the piston consistent with its axial movement, fluid pressure in both spool-working chambers is caused to apply equal and opposite axial thrusts on the spool to reverse the spool.

4. A motor as claimed in claim 1 in which the second pair of opposed faces of the spool are of different effective area.

5. A motor as claimed in claim 1 in which each of the pair of piston chambers is respectively in constant communication with one of the pair of spool-working chambers and each piston chamber has associated therewith a port through which it is adapted to be exhausted and wherein, during axial movement of the piston, the port through which the contracting piston chamber is exhausting is adapted to be closed by the piston towards its end of stroke and thereafter fluid pressure in the contracting piston chamber and spool working chamber in communication therewith applies an axial thrust to the spool which equalizes the opposing axial thrust applied to the spool by fluid pressure in the expanding piston chamber and spool-working chamber in communication therewith.

35. 6. A motor as claimed in claim 5 wherein fluid under pressure is delivered into the expanding piston chamber from the spool-working chamber in communication therewith and the spool-working chambers are adapted respectively to communicate with fluid pressure by way of one of a pair of fluid inlet ports controlled by the spool to be alternately opened and closed to their respective spool-working chambers so that with the spool at an end of its stroke the expanding piston chamber communicates with the spool-working chamber which is open to fluid pressure and the contracting piston chamber communicates with the spool-working chamber which is closed to fluid pressure.

7. A motor as claimed in claim 6 wherein the pair of fluid inlet ports are so controlled by the spool that in no position of the spool are they simultaneously closed to their respective spool-working chambers.

8. A motor as claimed in claim 5 in which two ports are provided in the piston cylinder through one of which ports each piston chamber is respectively adapted to be exhausted, said two ports communicating respectively with two ports in the spool cylinder which are alternately opened and closed to communication with exhaust by reciprocation of the spool, and wherein said two ports in the spool cylinder are so arranged and controlled by the spool that in no position of the spool are said ports simultaneously open to exhaust and, with the spool at an end of stroke position, the port in the spool cylinder which communicates with the expanding piston chamber is closed by the spool to exhaust and the port in the spool cylinder which communicates with the contracting piston chamber is open to exhaust and, on reversal of the spool, the port in the spool cylinder which communicates with exhaust is adapted to be closed by the spool prior to fluid pressure being admitted to its respective piston chamber and the port in the spool cylinder which is closed to exhaust is adapted to be opened by the spool to communication with exhaust subsequent to fluid pressure being cut off from its respective piston chamber.

9. A motor as claimed in claim 1 wherein two control ports are provided in the spool cylinder each of which is adapted to respectively communicate with one of the pair of spool-biasing chambers.

ing chambers, the control ports being controlled by reciprocation of the spool to be alternately opened and closed to their respective spool-biasing chambers and with the spool at an end of its stroke one control port is open and the other control port is closed to its respective spool-biasing chamber, the closed control port being associated with the spool-biasing chamber which, if subjected to fluid pressure, would urge the spool away from its said end of stroke position; said control ports being adapted to communicate alternately with fluid pressure and exhaust during reciprocation of the piston so that, with the spool at an end of its stroke, when the piston reaches an end of its stroke consistent with the spool in said end of stroke position the closed control port communicates with fluid pressure and the open control port and thereby its respective spool-biasing chamber communicates with exhaust and reversal of the spool causes the spool to open the control port in communication with fluid pressure to its respective spool-biasing chamber to urge the spool to its other end of stroke position.

10. A motor as claimed in claim 9 wherein the two control ports are so located and controlled by the spool that in no position of the spool are they simultaneously closed to their respective spool-biasing chambers.

11. A motor as claimed in claim 9 wherein each of the two control ports respectively communicates with one of two ports in the piston cylinder, each of the two ports in the piston cylinder being adapted to respectively communicate with one of the pair of piston chambers so that with the spool at an end of stroke position the control port which is closed by the spool communicates with the expanding pressure chamber and the control port which is open to its associated spool-biasing chamber communicates with exhaust when the piston reaches its end of stroke position.

12. A motor as claimed in claim 11 wherein the two ports in the piston cylinder which communicate with the control ports are so located and controlled by the piston that in no position of the piston are they simultaneously closed to communication with their respectively associated piston chambers.

13. A motor as claimed in claim 11 in which the piston defines with its cylinder a piston transfer chamber located axially between the pair of piston chambers and wherein said piston transfer chamber is in constant communication with exhaust and the two ports in the piston cylinder which communicate with the control ports are so located and controlled by the piston that during reciprocation of the piston each such port alternately communicates with its respectively associated piston chamber and the piston transfer chamber.

14. A motor as claimed in claim 13 in which the two ports in the piston cylinder which communicate with the control ports are so located and controlled by the piston that in no position of the piston are they simultaneously open to communication with the piston transfer chamber.

15. A motor as claimed in claim 1 in which fluid pressure is caused to be admitted to the other spool-biasing chamber by way of valve means responsive to axial movement of the piston.

16. A motor as claimed in claim 15 wherein said valve means is adapted to be actuated to admit fluid pressure to the said other spool-biasing chamber immediately before the port through which the contracting piston chamber exhausts is closed by the piston.

17. A motor as claimed in claim 15 in which the valve means comprises cooperating ports and lands between the piston and its cylinder.

18. A motor as claimed in claim 9 in which fluid pressure is caused to be admitted to the other spool-biasing chamber by way of valve means responsive to axial movement of the piston, and in which the spool cylinder has a pair of signalling ports each of which is adapted to respectively communicate with one of the pair of spool-biasing chambers, the signalling ports being controlled by reciprocation of the spool to be alternately opened and closed to their respective spool-biasing chambers and with the spool at an end of its stroke one

signalling port is open and the other signalling port is closed to its respective spool-biasing chamber, the open signalling port being associated with the spool-biasing chamber which, if subjected to fluid pressure, would urge the spool away from its said end of stroke position; said signalling ports being adapted to communicate with fluid pressure and being controlled for such communication by way of said valve means; and wherein for each spool-biasing chamber, the signalling port and control port respectively associated therewith are so located and controlled by the spool that in no position of the spool are they simultaneously closed to their respective spool-biasing chamber.

19. A motor as claimed in claim 18, wherein for each spool-biasing chamber, the signalling port associated therewith is adapted to communicate by way of said valve means with fluid pressure at the control port associated therewith.

20. A motor as claimed in claim 1 in which fluid under pressure is caused to be admitted to the other spool-biasing chamber by way of bleed passage means which is in constant communication with said other spool-biasing chamber and is adapted to communicate with fluid pressure during expansion of a piston chamber consistent with the spool at said end and to communicate with exhaust during contraction of a piston chamber consistent with the spool at the other end of its stroke.

21. A motor as claimed in claim 9 in which fluid under pressure is caused to be admitted to the other spool-biasing chamber by way of bleed passage means which is in constant communication with said other spool-biasing chamber and is adapted to communicate with fluid pressure during expansion of a piston chamber consistent with the spool at said end and to communicate with exhaust during contraction of a piston chamber consistent with the spool at the other end of its stroke, and in which each spool-biasing chamber and control port respectively associated therewith are in constant communication by way of a bleed passage.

22. A motor as claimed in claim 8 in which fluid under pressure is caused to be admitted to the other spool-biasing chamber by way of bleed passage means which is in constant communication with said other spool-biasing chamber and is adapted to communicate with fluid pressure during expansion of a piston chamber consistent with the spool at said end and to communicate with exhaust during contraction of a piston chamber consistent with the spool at the other end of its stroke, and in which each spool-biasing chamber and control port respectively associated therewith are in constant communication by way of a bleed passage.

23. A motor as claimed in claim 1 wherein auxiliary valve means is provided which is adapted to be actuated when the piston is located at or towards an end of stroke position and, with the spool at an end of stroke position, actuation of said auxiliary valve means admits fluid pressure to the spool-working chamber which, when pressurized urges the spool to its other end of stroke position.

24. A motor as claimed in claim 23 in which means is provided by which said auxiliary valve means cannot be actuated to admit fluid pressure to said spool-working chamber while said spool-working chamber communicates with exhaust.

25. A motor as claimed in claim 5 wherein auxiliary valve means is provided which is adapted to be actuated when the piston is located at or towards an end of stroke position and, with the spool at an end of stroke position, actuation of said auxiliary valve means admits fluid pressure to the spool-working chamber which, when pressurized urges the spool to its other end of stroke position, and in which, during axial movement of the piston, the auxiliary valve means is adapted to be actuated to admit fluid pressure to said spool-working chamber only when the piston is located at a position in which the port through which the contracting piston chamber exhausts is closed by the piston from communication with said piston chamber.

26. A motor as claimed in claim 25 in which the auxiliary valve means is adapted to admit fluid pressure into the con-

tracted piston chamber and therethrough into the spool-working chamber in communication with the contracted piston chamber.

27. A motor as claimed in claim 15, in which the valve means comprises cooperating ports and lands between a piston rod and a bore through which it is slid able.
